(57) **CLAIM**

The ornamental design for a front cover for a headset, as shown and described.

DESCRIPTION

FIG. 1 is a front perspective view of a front cover for a headset showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a rear perspective view thereof.

The broken lines of the headset in FIGS. 1 through 8 define the bounds of the claimed design and form no part of thereof.

1 Claim, 5 Drawing Sheets

FIG. 1

FIG. 2

FIG. 3

FIG. 4**FIG. 5**

FIG. 6**FIG. 7**

FIG. 8
